UNITED STATES PATENT OFFICE.

MICHAEL JOSEPH KENNY, OF CHICAGO, ILLINOIS, ASSIGNOR OF ONE-HALF TO ROBERT C. BOSS, OF WILMETTE, ILLINOIS.

DOOR HOLDER AND STOP.

1,073,243.

Specification of Letters Patent. Patented Sept. 16, 1913.

Application filed December 23, 1912. Serial No. 738,194.

To all whom it may concern:

Be it known that I, MICHAEL J. KENNY, a citizen of the United States, and a resident of the city of Chicago, county of Cook, 5 and State of Illinois, have invented certain new and useful Improvements in Door Holders and Stops, of which the following is a specification.

My invention relates to improvements in 10 door holders and stops and has for its object the production of a device of this character which will be of improved construction and efficient in use.

Other objects will appear hereinafter. 15 The invention consists in the combinations and arrangements of parts hereinafter described and claimed.

The invention will be best understood by 20 reference to the accompanying drawings forming a part of this specification, and in which,

Figure 1 is a side elevation of the upper end portion of a door frame and door to which is applied a device embodying my 25 invention, Fig. 2 is a horizontal section taken on substantially line $x-x$ of Fig. 1, Fig. 3 is an enlarged sectional detail of the pivotal connection between the jointed bar included in the construction and the door, 30 and Figs. 4 and 5 are enlarged detail sections taken on lines $y-y$ and $z-z$ respectively of Fig. 2.

The preferred form of construction as 35 illustrated in the drawing comprises a door 1 which is hingedly secured at 2 in the usual door frame 3. Said door and frame are connected by a bar 4 one end of which is pivotally secured to the under side of the upper bar of the frame 3 through the medium of a member 5, the opposite end of 40 said bar being pivotally connected at 6 with a plate 7 which is fastened to the inner side of the door adjacent the upper edge thereof. Interposed in the bar 4 is a pivotal joint 8 45 whereby, when the door is in closed position said bar will fold together as shown in Fig. 2. When the door is in open position as shown in dotted lines in Fig. 2, said bar will be in extended position, the same

50 being held or releasably locked in this position and hence the door in open position by means of a hook 9 pivotally secured to the bar 4 adjacent the joint 6, said hook member being adapted to engage an eye 9'

provided at one end of the plate 7, as 55 clearly shown in dotted lines in Fig. 2.

Arranged between the pivotal joint 6 and the eye 9' is a housing 10 the outer end of said housing being slotted at 11 in order to accommodate the adjacent portion of bar 4 60 when in extended position as clearly shown in Fig. 3. Loosely mounted in the housing 10 is a member 12 normally held at its outer terminal of movement by a helical compression spring 13. When the bar 4 is in engagement with the slot 11 the former will 65 depress the member 12 against the influence of spring 13 and so that upon release of said bar through disengagement of hook 9, said member 12 will press the adjacent section 70 of bar 4 outwardly and thereby cause outward breaking of the joint 8 in said bar. This is of advantage in that without such provision it would be necessary to break the joint 8 by hand and such a 75 provision is of further advantage in that it obviates the possibility of inward breaking of the joint 8 as will be readily understood. The member 12 also serves as a bumper, as will be observed, since it absorbs the shock which would otherwise be incidental to suddenly unfolding the bar 4 into extended position.

A device of the construction set forth 85 is simple and economical in construction and hence of little cost to manufacture. The device may be readily and easily arranged for use in conjunction with a door and is efficient in use.

While I have illustrated and described 90 the preferred form of construction for carrying my invention into effect, this is capable of variation and modification without departing from the spirit of the invention. I, therefore, do not wish to be limited to the 95 precise details of construction set forth, but desire to avail myself of such variations and modifications as come within the scope of the appended claims.

Having described my invention what I 100 claim as new and desire to secure by Letters Patent is:

1. In a device of the class described, the combination with a door frame and a door 105 swingingly mounted therein, of a bar having a pivotal joint intermediate its ends, one end of said bar being pivotally secured to said door, the opposite end of said bar

being pivotally secured to the door frame; means for maintaining said bar in extended position to hold said door open; and means on said door for causing said joint to break 5 outwardly when said bar is released, substantially as described.

2. In a device of the class described, the combination with a door frame and a door 10 swingingly mounted therein, of a bar having a pivotal joint intermediate its ends, one end of said bar being pivotally secured to said door, the opposite ends of said bar being pivotally secured to the door frame; means for maintaining said bar in extended 15 position to hold said door open; and spring compressed means on said door for causing said joint to break outwardly when said bar is released, substantially as described.

3. In a device of the class described, the 20 combination with a door frame and a door swingingly mounted therein, of a bar having a pivotal joint intermediate its ends, one end of said bar being pivotally secured to said door, the opposite ends of said bar being pivotally secured to the door frame; means for maintaining said bar in extended 25 position to hold said door open; and a spring compressed bumper on said door adapted to contact with said bar when in extended position and cause said joint to break outwardly when said bar is released, 30 substantially as described.

4. In a device of the class described the 35 combination with a door frame and a door swingingly mounted therein, of a bar having a pivotal joint intermediate its ends, one end of said bar being pivotally secured to said door, the opposite end of said bar

being pivotally secured to the door frame; a hook on said bar adapted for engagement 40 with an eye on said door for maintaining said bar in extended position to hold said door open; and a spring pressed bumper on said door adapted to contact with said bar when in extended position and cause said 45 joint to break outwardly when said bar is released, substantially as described.

5. In a device of the class described the combination with a door frame and a door swingingly mounted therein, of a bar having a pivotal joint intermediate its ends, one end of said bar being pivotally secured to said door, the opposite end of said bar being pivotally secured to the door frame; a hook on said bar adapted for engagement 50 with an eye on said door for maintaining said bar in extended position to hold said door open; a housing on said door adjacent the point of connection therewith of said bar; a spring compressed 55 member in said housing, the upper end of said housing being slotted for receiving the adjacent portion of said bar when in extended position, said bar, when in extended position, causing depression of said 60 spring compressed member and so that when said door is released said joint will be caused to break outwardly, substantially as described.

In testimony whereof I have signed my 70 name to this specification in the presence of two subscribing witnesses.

MICHAEL JOSEPH KENNY.
